[57] CLAIM

The ornamental design for an audio cassette storage album, as shown and described.

DESCRIPTION

FIG. 1 is a perspective view of an audio cassette storage album showing our new design in the open position, the exterior surface of the cover being plain and unornamented;

FIG. 2 is an enlarged scale perspective view of the connected cassette holders shown in FIG. 1, the album cover being removed for clarity;

FIG. 3 is a top plan view of FIG. 2;

FIG. 4 is a front elevational view thereof; and

FIG. 5 is a side elevational view thereof.
